UNITED STATES PATENT OFFICE.

ALEXANDER KONOFF, OF NEW YORK, N. Y., ASSIGNOR TO OVERLAND METAL NOVELTY CO. INC., OF NEW YORK, N. Y., A CORPORATION OF NEW YORK.

EYE SET.

Application filed April 30, 1926: Serial No. 105,678.

This invention relates to an eye set for dolls and similar toys, and is in the nature of an improvement over the eye set shown and described in my pending application

5 Serial No. 95,198.

An object of the present improvement is to provide an efficient means for insuring a proper operative positioning of the eyes within the eye sockets of the doll head.

10 A further object is to provide means whereby by the act of attaching the eye set within the doll head the eyes will be adjustably moved and accurately located with respect to the eye sockets of the head so as to be free of binding engagement against the walls of said sockets.

15 A further object is to so construct the eye set that it may be quickly and easily attached within the doll head, by relatively unskilled labor, and so that eye sets so attached will be uniformly efficient in their co-operative movements with respect to the eye sockets.

20 A further and more detailed object is to provide an eye set including a supporting carrier for the eyes, said carrier being adapted to be attached to the material of the doll head and including elements which, by the act of attachment to the doll head, will function to ease the eyes of the set away from the eye sockets of the head into a certain and definitely prescribed relationship with the eye sockets.

25 A further detailed object is to so construct the eye set that it may be placed in position within a doll head with the eye members of the eye set resting firmly into and against the eye sockets of the head and so that it may be then operated upon to fix it within the head and to simultaneously ease the eye members away from binding engagement with the walls of the sockets.

30 A further object is to avoid the necessity for using springs to hold the eyes in co-operative engagement with the eye sockets.

35 Other objects and aims of the invention, more or less specific than those referred to above, will be in part obvious and in part pointed out in the course of the following description of the elements, combinations, 40 arrangements of parts and applications of principles constituting the invention; and the scope of protection contemplated will be indicated in the appended claims.

In the accompanying drawings which are

to be taken as a part of this specification, 55 and in which I have shown merely a preferred form of embodiment of the invention:

Fig. 1 is a rear elevational view of an eye set constructed in accordance with this invention, said set being shown as it appears when in position within a doll head, the doll head being shown in vertical section.

Fig. 2 is a horizontal sectional view taken substantially upon the plane of line II—II 65 of Fig. 1, and

Fig. 3 is a view similar to that appearing in Fig. 2 but illustrating the eye set in its final attached position whereas in the illustration Fig. 2 the eye set is shown before 70 final attachment of the supporting carrier with the material of the head.

Referring to the drawings for the purpose of a detailed description of the exemplary structure illustrated therein, the reference 75 character L indicates a doll head. Although a doll head is herein shown and referred to, nevertheless it will be understood that this invention is equally well adapted for use in connection with any other toy or toys in 80 which moving eyes are utilized.

The doll head illustrated has the usual spaced eye sockets 1 and 2 at opposite sides of the central nose portion 3. Beyond the eye sockets 1 and 2 the cheek portions of 85 the head are preferably thickened as at 4 and 5 so as to reinforce the cheek portions in the region adjacent to the eye sockets and so as to provide opposite interior wall surfaces as 6 and 7 which are substantially 90 parallel to each other and thereby adapted to constitute proper and substantial supports for the eye set.

The eye set comprises two main elements, 95 namely a supporting carrier G and an eye member H.

The supporting carrier G consists of a body portion 8 which is adapted to extend horizontally across the interior of the doll head from cheek portion to cheek portion 100 and which has an eye carrying portion 9 intermediate its length adapted to extend forwardly from the body portion for supporting the eye member H.

The eye member H consists of a cross rod 105 10 at opposite ends of which are mounted two eyes as 11 and 12, said eyes being adjustably connected with the cross rod in

any desired manner such for instance as shown in my Patents Nos. 1,566,105, 1,580,051, 1,578,834, and 1,566,966 or otherwise.

The body portion 8 of the carrier G is made from an elongated piece of sheet metal bent into channel shape, and within the channel or guide-way it carries a pair of attaching members at 13 and 14.

The attaching members 13 and 14 are longitudinally slideable along the channel and their outer end portions are formed with prongs as 15 and 16 which, when the attaching members are slid outwardly away from each other, sink into the reinforced walls 6 and 7 of the head.

Before the insertion of this eye set into the doll head the attaching members 13 and 14 are of course in their innermost or normal positions, that is so that their inner ends as 17 and 18 abut together, or nearly so, and their outer ends do not project objectionably beyond the outer ends of the body 8, and their movement outwardly for driving the prongs 15 and 16 into embedded relation within the cheek portions of the head is not performed until after the eye set has been moved into position with the eyes 11 and 12 held firmly into and against the eye sockets 1 and 2 of the head.

Since it is intended that when the attaching members have been once driven outwardly into the cheek portions of the head they shall thereafter maintain their positions for continuing to properly support the eyes, the attaching members are fitted so tightly within the channel of the body 8 that retrogressive movement of the attaching members will not be likely.

Each of the attaching members 13 and 14 is provided with a suitable aperture as 19, or other appropriate means, for co-operating with a tool to be used in operating the attaching members. The body 8 is also provided with an aperture as 20 or other appropriate means, which may be usable in conjunction with the tool and the openings 19 to assist in the proper operation of the attaching members by the tool as will be more fully set forth in an application presently to be filed.

When the supporting carrier has been once placed in position and the attaching members 13 and 14 have been driven outwardly said carrier will thereafter be rigid with the doll head.

The eye carrying portion 9 of the carrier G may take any desired form, its essential characteristic being simply that it serves as a pivot bearing for directly supporting the cross rod 10 of the eye member H. In the form illustrated it consists of a pair of arms as 21 and 22 projecting forwardly from the body 8 spaced apart, each of said arms having a slot as 23 therein providing mating bearings within which the cross rod 10 is

free to rotate and move longitudinally as may be required. It is particularly noted however that the inner end walls of the slots 23 provide positive abutments as 24 and 25 against which the cross rod bears so that the cross rod is held a definite distance from and parallel to the carrier G.

By reference to the illustration Figs. 2 and 3 it will be seen that the outer end portions of the attaching members 13 and 14, that is the pronged portion of said members, are bent slightly backwardly out of the normal plane of the carrier H.

In Fig. 2 the eye set is shown as it appears just prior to the entrance of the prongs into the walls 6 and 7 of the head. The eyes 11 and 12 are held close into and against the sockets 1 and 2 of the head and the inner walls 24 and 25 of bearing slots 23 are close against the cross rod 10. This is the position into which the eye set is moved and in which it is held preparatory to driving the attaching members into fixed relation in the cheeks of the doll head, it being understood that the tool or device employed for inserting and attaching the eye set within the head is of such form as to directly engage the carrier G and hold it in the position indicated preparatory to operating the attaching members.

In Fig. 3 the eye set is shown as it may appear after the attaching members have been driven to a desired depth within the cheek portions of the head, and here it will be noted that, by reason of the inclined, or rearwardly bent, disposition of the pronged ends of the attaching members, the act of moving the attaching members from the position Fig. 2 to the position Fig. 3 has caused the carrier G to move rearwardly a distance determined by the amount of incline or bend of the prongs and the distance to which the prongs are driven into the cheek portions of the head, the prongs while moving into the material of the head, merely following the inclined planes of the prongs. The extent to which the backward movement of the carrier is carried by this means may be thus determined with great accuracy and precision and the eyes be thus given a desired degree of free movement within the eye sockets. Even though the eye sockets may not themselves be accurate or may not have the full desired accuracy of fit relative to the eyes, or even if they contain an unintended slight perturbation or other feature which might interfere with the free movement of the eyes in operation, nevertheless these features would all be accounted for by the use of the present invention. When the eyes are introduced into the sockets as in Fig. 2 they would encounter the undesirable features and when the attaching members are driven home as in Fig. 3 the eyes would move away

from the undesirable features and thereby enable the unobstructed oscillatory movement of the eyes.

In all events, when the attaching members 5 are driven home as in Fig. 3 the eyes would have tight engagement neither with the eye sockets nor any parts thereof or with the rear walls 24 and 25 of the bearings 23. The amount of looseness of the eye member with 10 respect to these parts will be a definite and predetermined quantity so that the eyes will be both desirably close within the sockets for proper external appearance and desirably loose with respect to its bearings and the 15 sockets to enable unobstructed oscillatory motion at all times. It may be correctly said therefore that the movement of the attaching members into embedded relation within the material of the doll head causes an adjusting movement of the supporting carrier and of the eye member suitable to bring these parts into a desired adjusted position for proper functioning.

20 The channel or guide-way provided in the carrier G for slidably supporting the attaching members is a straight line guide-way so that said attaching members are adapted to move in a straight line away from each 25 other, the outer ends, or pronged portions of said attaching members being bent backwardly from said straight line and into angular relation with each other.

Light springs as 26 and 27 may be arranged 30 between the carrier G and the eye member H for urging the eye member toward the sockets of the head if desired but these are ordinarily not required.

Any suitable means may be employed for 35 causing the eye member to oscillate as the doll is moved from reclining position to upright position, etc., and for this purpose the drawing illustrates the usual weight as 28 connected by an arm 29 with the cross rod 40 10. The gravity movements of the weight, under change of the position of the doll, will oscillate the cross rod and cause the eyes to move between "open" and "closed" positions.

50 The parallel disposition of the surfaces or walls 6 and 7 of the doll head is a matter of considerable importance to the practical use of this invention in quantity production. In order that a tool for driving the attaching 55 members into these surfaces or walls may be used with suitably uniform efficiency by relatively unskilled hands the tool will preferably be made to move the attaching members outwardly a given distance for all eye sets attached by it. Since the eye sets are 60 of a uniform given size, and the prongs at the ends of the attaching members all of the same uniform angularity, and since the degree of backward movement of the carrier 65 incident to the driving in of the prongs is

dependent upon the depth to which they are driven, it is apparent that the walls in all of the doll heads should be of uniform relation to each other not only as to parallelism but also as to distance apart. Different eye 70 sets will undoubtedly vary to some degree in the precise relationship of the supporting carriers with the eye members, particularly as to exact parallelism of these two parts, owing to difference in depth of the slots 23, 75 or one eye socket of the doll head may be ground out a little more than the other or may be otherwise a little further forward or rearward of the other. For these and other 80 various reasons the prongs of the attaching members will not always engage the exact same relative point on the walls 6 and 7 of different doll heads. In different heads the point of engagement may vary to a considerable extent. 85

In order for the attaching members in succeeding doll heads to sink a uniform distance into the walls 6 and 7, and thus produce uniform results in the adjusting movement imparted to the eye set it is quite necessary that the walls 6 and 7 present surfaces which are practically parallel and which are of such extent as that substantially the same result will be attained by a given outward thrust of the attaching members into different portions of said surfaces. 90

As many changes could be made in this construction without departing from the scope of the invention as defined in the following claims, it is intended that all matter contained in the above description or shown in the accompanying drawings, shall be interpreted as illustrative only and not in a limiting sense. 100

For instance it is pointed out that the principles of this invention might be utilized in connection with the attachment of eyes within doll heads or the like where the eyes are intended to be immovably held within the eye sockets. In this instance the pronged portions of the attaching members would simply be bent forwardly instead of backwardly, whereupon the movement of the attaching members into the material of the head would urge the eyes forwardly and thus cause them to bind immovably in any given position within the eye sockets. 110

Having thus described my invention, what I claim as new and desire to secure by Letters Patent is:—

1. An eye set comprising a pair of eyes and a supporting carrier therefor, attaching means comprised in said carrier by which to attach the carrier in position within a doll head, said attaching means consisting of a pair of pronged members movable with respect to each other to drive the prongs thereof into embedded relation within the material of the head, and said prongs being inclined with respect to each other to 125 130

thereby cause an adjusting movement of the eyes with respect to the head co-incident with the movement of the prongs into the material of the head.

5. 2. An eye set comprising a pair of eyes and a supporting carrier therefor, attaching means comprised in said carrier by which to attach the carrier in position within a doll head, said attaching means consisting of a pair of pronged members movable with respect to each other to drive the prongs thereof into embedded relation within the material of the head, the carrier providing a guide-way within which said attaching members are slidably movable in a straight line away from each other during movement of the prongs thereof into the material of the head, and the prongs of said attaching members being inclined with respect to said straight line to thereby cause an adjusting movement of the eyes with respect to the head co-incident with movement of said prongs into the material of the head.

25. 3. The combination with a doll head having eye sockets, of an eye set therefor comprising a pair of eyes, attaching means for attaching said eyes within the doll head, said attaching means comprising parts movable to engage parts of the doll head for attaching the eye set within the doll head, and force producing means to positively adjustably move a part of the eye set with respect to the doll head coincident with the movement of said movable parts to attaching position.

40. 4. An eye set comprising a pair of eyes and a supporting carrier therefor, attaching means comprised in said carrier by which to attach the carrier in position within a doll head, said attaching means consisting of a pair of attaching members movable with respect to each other into engagement with the doll head, and said attaching members having force producing parts for engaging the doll head arranged to cause a positive adjusting movement of the carrier with respect to the doll head upon movement of the attaching members to attaching position.

55. 5. An eye set comprising a pair of eyes and a supporting carrier therefor, attaching means comprised in said carrier by which to attach the carrier in position within a doll head, said attaching means consisting of a pair of pronged attaching members movable with respect to each other to drive the prongs thereof into embedded relation within the material of the head, and force producing means whereby the act of driving said prongs into the material of the head will cause an adjusting movement of the carrier with respect to the head.

6. As an article of manufacture, a sup-

porting carrier for the eye member of an eye set, said supporting carrier comprising a body portion shaped to provide a guideway therein, and being provided with means to pivotally support the eye member, and a pair of attaching members slidable along the guideway of the body portion, said attaching members having attaching portions adapted to engage the material of a doll head, and the attaching portion of one of said attaching members being disposed at an angle with respect to the attaching portion of the other attaching member.

7. As an article of manufacture, a supporting carrier for the eye member of an eye set, said supporting carrier comprising a body portion shaped to provide a straight line guideway therein and provided with means to pivotally support the eye member, a pair of attaching members, slidably received within the guideway of the body portion to slide in a straight line away from each other to drive their outer ends into embedded relation within the material of a doll head, and said outer ends being inclined with respect to said straight line.

8. As an article of manufacture, a doll head having the usual eye sockets and cheek portions, and said cheek portions being constructed interiorly of the head to provide opposite side wall portions adjacent to said eye sockets respectively, which portions may be readily penetrated by prongs driven thereto and which present flat surfaces interiorly of the head parallel to each other both vertically and horizontally of the head adapted to serve as regions for the attachment of an eye set.

9. In an eye set, comprising a pair of eyes and a carrier therefor, the combination therewith of force producing means comprised in said carrier operable simultaneously to attach the carrier within a doll head and to positively adjustably move said carrier with respect to the head.

10. An eye set for doll heads, said eye set comprising a pair of eyes and a supporting carrier therefor, a member movable with respect to said carrier, said member having a pointed portion thereon adapted to be projected into the material of the head, and force producing means embodied in said pointed portion to cause an adjusting movement of the carrier coincident with movement of said pointed portion into the material of the head.

11. An eye set comprising a pair of eyes, a cross rod extending between and connecting the eyes, a supporting carrier upon which the cross rod is rotatably mounted, said supporting carrier comprising a main body portion and a pair of attaching members, said main body portion having a part providing a bearing for the cross rod and having another

- part providing a guideway for the attaching members whereby the attaching members are slideable away from each other to engage opposite side wall portions of a doll head 5 for retaining the carrier rigidly in position within the doll head, and the portions of said attaching members which engage the walls of the doll head being relatively inclined, whereby to cause an adjusting movement of the carrier coincident with movement of the attaching members to attaching position.
12. In an eye set comprising a pair of eyes intended to engage the eye sockets of a doll 15 head, a carrier for said eyes, and resilient means comprised in the carrier to resiliently urge the eyes toward the sockets, the combination therewith of force producing means operable simultaneously to attach the carrier 20 within the doll head and to relieve the pressure of the resilient means.
13. The combination with a doll head having eye sockets, of an eye set therefor comprising a pair of eyes, attaching means for 25 attaching said eyes within the doll head, said attaching means comprising parts movable to engage parts of the doll head for attaching the eye set within the doll head, and force producing means to positively and 30 progressively adjust a part of the eye set with respect to the head coincident with the pro-
- gression of movement of said movable parts towards final attaching position.
14. In an eye set comprising a pair of eyes, a support for said eyes, and attaching means operative to attach the support to a doll head, the combination therewith of force producing means to positively adjustably move said support upon operation of the attaching means. 40
15. The combination with a doll head having eye sockets, of an eye set therefor comprising a pair of eyes, attaching means for attaching said eyes within the doll head, said attaching means comprising parts movable 45 to engage parts of the doll head for attaching the eye set within the doll head, and force producing means to positively adjustably move a part of the eye set backwardly away from the eye sockets of the head coincident with movement of said movable parts to attaching position. 50
16. In an eye set comprising a pair of eyes, a support for said eyes, and attaching means operative to attach the support to a doll head, the combination therewith of force producing means to progressively adjust said support coincident with the operation of the attaching means. 55

In testimony whereof I affix my signature.

ALEXANDER KONOFF.
